PARTICLE APPORTIONING DEVICE

Morris Cohen, Kansas City, Mo., and Gerald A. Jorgenson, Chicago, Ill., assignors to Interstate Bakeries Corporation, Kansas City, Mo., a corporation of Delaware

Application November 23, 1942, Serial No. 466,614

7 Claims. (Cl. 259—14)

1

This invention relates to a particle apportioning device more particularly for edible particles such, for example, as raisins or currants, which are introduced into the dough for the making of sweet rolls, raisin bread, or the like, in large commercial bakeries.

While the apportioning of particles of certain types such, for example, as flour, granulated nuts, and similar generally dry materials encounters relatively few difficulties and these may be introduced by means of hoppers, the handling of other types of particles such as raisins involves problems not encountered in the handling of more dry particles, the raisins, for example, being naturally somewhat sticky and tending to pack together so as to clog any device such as a hopper or other conventional apportioning means wherein the particles are moved largely under the influence of gravity, with the weight of a quantity thereof constantly pressing upon the particles as they move.

In the present invention, a unitary portable device is provided in which the particles are not moved merely by gravity but are maintained in circulation during the apportioning process, partially by gravity and partially by a positive mechanism therefor, whereby the raisins are kept relatively dry and loose at all times, and the raisins are finally apportioned through a variable restricted opening.

These and other objects and advantages will be apparent from the following description, taken together with the accompanying drawings, in which—

Figure 1 is a side elevational view of a device embodying the present invention, parts being shown in section for clearness of description, and an associated conveyor device;

Figure 2 is a cross-sectional view, partially in end elevation, taken on the staggered line 2—2 of Fig. 1 but with the raisin circulation indicated, and looking toward the delivery end of the device, driving parts being omitted; and

Figure 3 is a fragmentary perspective view of the discharge end of the conveyor of the present device and one end of the associated conveyor, indicated also in Fig. 1.

Referring in detail to the illustrative construction shown in the drawings, the unitary device of the present invention is mounted on a pedestal designated generally by the numeral 10, having four legs 11 which terminate at their lower ends in casters 12 whereby the device is mobile. Adjacent their upper ends, the pedestal legs 11 rotatably carry a pair of shafts 13 and 14, each run-

2

ning from front to rear of the device in parallel relation at each side thereof, and each carrying a pair of bearing disks 15 and 16, making four such disks in all. The bearing disks 15 are here shown carried between the legs 11, and the bearing disks 16 to the rear of the legs where the shafts 13 and 14 there overhang. Resting upon the bearing disks 15 is a rotatable cylindrical drum 17 held thereon by its weight. The drum here represents a depositing element. Adjacent the forward end of the drum, its periphery carries an annular channel piece 18 which receives the bearing disks 15 and adjacent its rear end a similar annular channel piece 19 which receives the bearing disks 16. Thus the drum is guided in its rotation as presently described and its axial position during rotation is maintained with respect to the pedestal 10.

For driving the drum 17, its periphery may also carry an external ring gear 20 which meshes with a pinion 21 keyed to the shaft 13, this shaft being a driving shaft and it is continued forwardly of the legs 11 to terminate in a bevel gear 22, which meshes with another bevel gear 23 keyed to a stub shaft 24. The stub shaft 24 is rotatably mounted in a pair of brackets 25, supported by a platform 26 projecting from the forward end of the pedestal 10. Diagonal braces 27 extending from the platform to the legs 11 may reinforce the platform which also provides a support for an electric motor 28, the output shaft 29 of which is in driving relation by means of chain belt 30 with a sprocket 31 also keyed to the stub shaft 24. Thus, by means of the usual electric wiring which need not be here shown, the motor 28 may be connected to a source of electric power and caused to rotate the drum 17 on the pedestal 10 in the direction of the arrow 32 (Fig. 2) on a horizontal axis.

In accordance with the present invention, the drum surrounds one end of a depository element here represented by the conveyor device indicated generally by the numeral 33 and which comprises a frame having somewhat triangular side members 34 bolted as at 35 to a cross strut 36 connecting the upper ends of the forward legs 11 of the pedestal 10, which are shown extended upwardly beyond the rear legs to a point approximating the axis of the drum 17 and just in front of the forward end of the drum, the latter having a relatively large axial opening 37 in its forward end through which the conveyor 33 extends into the interior of the drum as well as forwardly thereof. For enhanced stability, the frame side members 34 extend downwardly in front of the

cross strut 36 and may be bolted as at 38 to another cross strut 39 carried by the legs 11 below the cross strut 36. At each end respectively of the frame members 34 are rotatably mounted the usual conveyor rollers 40 and 41, about which are entrained the endless conveyor belt 42 of canvas or the like.

The conveyor belt 42 as well as the drum may be driven by the motor 28. In this instance, the roller shaft for the roller 40 is extended laterally of the conveyor frame plates 34 to carry a sprocket 43 upon which is entrained an endless chain 44 also entrained with another sprocket 45 keyed to a stub shaft 45a mounted on the exterior of one of the frame members 34. A gear 46 also keyed to this shaft meshes with another gear 46a similarly mounted upon a stub shaft 46b which has keyed thereon a sprocket 46c. About the latter is entrained an endless chain 47 which is also entrained with a sprocket wheel 48 which is keyed to the stub shaft 24 along with the sprocket 31 and bevel gear 23. Thus rotation of the motor shaft 29 in a direction to rotate the drum 17 in the direction of the arrow 32 will also move the upper run of the conveyor belt 42 in the direction of the arrow 49.

The inner surface of the drum 17 is provided with a number of formations such as the lifter blades 50, three being here shown, which extend lengthwise of the cylindrical part of the drum 17 and project somewhat radially toward the axis of the drum. Forward of the cylindrical portion of the drum, the latter is desirably conical as at 51 margining the axial opening 37 and providing a guard to prevent particles lifted by the blades from falling through the opening 37. At its rear end, the drum has a door 52 which is received with a snug fit within the angled margin 53 of another axial opening in the drum, and which, when the door 52 is removed, may be employed to deposit raisins or the like into the drum for disposition as presently described.

Further in accordance with the present invention, the inner end of the conveyor 33 which is received within and surrounded by the drum 17 has associated therewith means whereby only some of the particles such as the raisins deposited in the drum and circulated by the blades 50, fall onto the conveyor, other particles falling back into the drum to be recirculated.

As shown in the drawings, an illustrative element for this purpose here includes a peaked hood designated generally by the numeral 54, and comprising a pair of spaced apart shield elements 55 and 56, which are in the form of inclined plates carried by the conveyor frame members 34 just above the inner end of the conveyor 42 as by brackets 57 bolted upon the outer faces of the frame members 34 respectively as at 58 to overhang the conveyor. The brackets 57 have a vertical portion at which they are bolted to the frame and an inwardly directed upwardly angling portion 59, in which is an elongated slot 60. Through each of the slots 60 passes the shank of a short screw-bolt 61 and this passes also through a perforation in the plate 55 or 56 as the case may be. On the upper surface of the plate and threaded on the shank of each of the bolts 61 is a thumb-nut 62. Thus the plates 55 and 56 may be adjustably clamped in position over the conveyor belt 42 normally with a longitudinal space or slot 63 therebetween, providing a restricted opening on both sides and which is selectively variable as here disclosed. Preferably the slot 63 is to one side of the peak 65 of the hood 54 and to accom-

plish this the plate 55 is wider than the plate 56 and its outer margin is bent downwardly as at 64, both to form the peak 65 and an edge 66 which approaches the edge 67 of the narrower plate 56 along a longitudinal line to one side of the longitudinal center line of the conveyor 43 but parallel therewith. The sliding adjustment here provided preserves a substantially uniform inclination for the shield plates which permits of a very fine stream of raisins for example.

To prevent particles from lodging between the conveyor 42 and the frame members 34, the latter desirably carry longitudinal angle strips 68, one angular portion of each of which rests on the upper edge of the frame and the other angular portion of which depends inwardly over the side margin of the conveyor belt and into close but non-frictional proximity therewith.

The operation of the device is as follows:

Having deposited a supply of raisins or the like into the drum 17 as at 69 and having replaced the door 52 to close the rear end of the drum, the operator starts the motor 28 thus causing the drum to rotate in the direction of the arrow 32 and the upper run of the conveyor to move in the direction of the arrow 49. As the drum rotates, some of the raisins which lie loosely in the lower part of the drum are picked up by a blade 50 and carried thereon to the upper part of the drum. As the blade approaches its zenith, the raisins fall off therefrom under the influence of gravity as at 70 and in falling strike the hood 54. Some of the raisins drop through the slot 63 onto the conveyor belt 42, while others, deflected by the hood, fall back into the mass of raisins 69 in the lower part of the drum to be again picked up by a later oncoming blade 50. Since the raisins falling off a blade as at 70 have some momentum due to the rotation of the drum, they will not fall in a straight line but will have a somewhat arcuate trajectory and the slot 63 may be adjusted, by the adjustment means for the plates 55 and 56 already referred to, so as to be in this path. Due to various causes, the raisins will not all have the same trajectory, but it has been found that a mean arc thereof will pass to the right of the peak 65, looking at Fig. 2, that is, the proximate side of the hood 54 as the blades rotate, and through the slot 63 whereby many of the raisins will pass through the slot onto the belt.

The raisins carried by the conveyor belt 42 travel outwardly of the drum and may fall off the discharge end 71 of the conveyor 33, as here shown, onto a strip of dough 72 moving in the direction of the arrow 73 on an associated conveyor 74. The dough strip 72 may be produced in flattened elongated form by means which forms no part of the present invention, but which may be in accordance with the Cohen et al. co-pending application Serial No. 441,580, filed May 4, 1942, and may, after having had the raisins deposited thereon in accordance with the present invention, be then treated and coiled on a longitudinal axis as described in another co-pending Cohen et al. application, Serial No. 429,764, filed February 6, 1942, to form bakery sweet rolls or the like.

As shown in Fig. 3, the conveyor 33 is arranged at right-angles to the associated conveyor 74, and the unitary device of the present invention may be disposed in such position with the conveyor 33 overhanging the conveyor 74 at any suitable point along the latter, the ready mobility of the pedestal 10 as by the casters 12 making this possible. Furthermore, the particular arrangement of the conveyor 33, supported as it is in cantilever arrange-

ment on the pedestal 10, avoids interference with the standard 75 of the associated conveyor 14 and permits it to be received in similar cantilever arrangement within the drum 17 at the receiving end of the conveyor 33.

The sloping or peaked character of the hood 54 provides a deflector for causing raisins which drop off the blades and which do not fall through the slot 63 to fall back into the bottom of the drum and to be re-tumbled, such tumbling contributing to maintaining the raisins in dry and cool condition.

So arranged and operated, the device of the present invention keeps the raisins constantly circulated so that they do not become heated and sticky by their own mass, thus avoiding agglomerations of the raisins which might result in too many raisins in one part of the dough and too few in another part and providing better and more uniform distribution thereof throughout the dough strip 12.

It will be understood that if a greater number of raisins for a given linear distance of the dough strip 12 be desired, the plates 55 and 56 may be adjusted farther apart so as to widen the slot 63, and, conversely, if fewer raisins are desired per linear distance, the slot may be narrowed. In any case, raisins which fall off of a blade 50 approaching its zenith and which do not fall through the slot 63 to the conveyor 42 will fall back into the lower part of the drum and be recirculated, the peaked character of the hood 54 being of a sufficient declivity so as to exceed the angle of rest of the raisins and preventing lodging of the latter thereon.

The raisins in the bottom of the drum as at 69 are maintained constantly agitated by the blades 50 and prevented from objectionable packing which is common in the use of conical hoppers, screw-conveyors, and the like.

The gearing is desirably so arranged, as here shown, that the linear speed of the belt 42 is predetermined relatively to the peripheral speed of drum 17. Thus the belt moves a distance equal to the length of a blade 50 in the interval of time between which two successive blades approach their zenith, so that there are no marked gaps in the sequence of the raisins deposited on the conveyor, or so as to prevent overlap of successive streams so deposited.

What is here claimed is:

1. In a device of the class described, the combination with a conveyor, of a pair of spaced apart shield members providing a shield disposed over the conveyor providing a restricted opening between said shield members shielded on both sides thereof vertically aligned with and spaced above said conveyor, a rotatable drum surrounding the conveyor and shield members, blades in the drum for lifting particles disposed therein from the bottom of the drum to the top thereof and dropping them on said shield, whereby some of said particles pass through said opening onto the conveyor and others may fall back into the drum, means for rotating the drum and operating the conveyor, and means for adjusting the size of the opening between said shield members to vary the number of particles disposed on the conveyor during a given period of operation of the device, and to cause a controlled stream of particles to be deposited on said conveyor.

2. In a device of the class described, the combination with a conveyor, of a pair of spaced apart shield members providing a shield dis-

posed in the form of a peaked hood over the conveyor providing a restricted opening therebetween vertically aligned with and spaced above said conveyor, said opening being to one side of the peak in the hood, a rotatable drum surrounding the conveyor and shield members, blades in the drum for lifting particles disposed therein from the bottom of the drum to the top thereof and dropping them on said shield, whereby some of said particles pass through said opening onto the conveyor and others fall back into the drum, means for rotating the drum, means for operating the conveyor, and means for adjusting the size of the opening between said shield members to vary the number of particles disposed on the conveyor during a given period of operation of the device, while causing a controlled stream of particles to be deposited thereon.

3. In a particle apportioning device of the class described, the combination with a pedestal, of a drum rotatably carried thereon, one end of said drum having a central opening, a pair of parallel frame members mounted in cantilever arrangement on the pedestal, one end of each frame member extending through said central opening, an endless conveyor entrained on said frame members, a pair of spaced apart shield members providing a shield disposed in the form of a peaked hood over the conveyor having a restricted opening therein vertically aligned with and spaced above said conveyor, means for varying the extent of separation of said shield members to vary the extent of said last mentioned opening, blade formations in the drum for lifting particles disposed therein from the bottom of the drum to the top thereof and dropping them onto said shield whereby some of the particles fall through said opening onto the conveyor and others fall back into the drum, a platform carried on the pedestal below the conveyor frame, a motor mounted on the platform, power transmission means engaging the motor and the drum and conveyor respectively for causing the motor to drive both the drum and conveyor arranged whereby the belt may move a distance equal to the length of one of said formations in the interval of time between which two successive formations approach their zenith, whereby to cause a thin continuous stream of particles to be deposited on said belt and mobilizing means on the pedestal for ready portability.

4. In a particle apportioning device the combination of a longitudinally movable depository element, a rotary depositing element in vertically encircling proximity to the depository element and adapted to elevate the particles and drop them by gravity toward the depository element, a deflecting shield within the rotary element and partially covering the depository element, said shield including a pair of shield members inclined toward each other and extending longitudinally of the depository element and spaced apart in vertical alignment with said depository element, said shield members being arranged at substantially fixed inclinations with respect to each other and the depository element, and means for adjusting the distance apart of said shield members, said adjusting means comprising means for sliding at least one of the shield members toward and away from the other in their inclined planes, whereby to maintain the place where they are spaced apart in vertical alignment with said depository element while maintaining a substantially uniform angle for said shield members

with respect to each other and the depository element.

5. In a particle apportioning device the combination of a longitudinally movable depository element including an endless belt conveyor, a rotary depositing element in vertically encircling proximity to the depository element, circumferentially equally spaced apart longitudinally elongated blades on the inner face of said depositing element to elevate the particles and drop them by gravity toward the depository element, a deflecting shield within the rotary element and partially covering the depository element to cause a portion of such particles so dropped to be deflected from said depository element, means for rotating said depositing element and means for moving said depository element arranged whereby the belt conveyor moves a distance equal to the length of said blades in the interval of time between which two successive blades reach the same rotative position with respect to the shield whereby to prevent substantial overlapping of the particle streams on the depository element from successive blades.

6. In a particle apportioning device, the combination of a longitudinally movable depository element, a rotary depositing element in vertically encircling proximity to the depository element and adapted to elevate the particles and drop them by gravity toward the depository element, a deflecting shield within the rotary element and partially covering the depository element, said shield including a pair of shield members inclined towards each other and extending longitudinally of the depository element and spaced apart in vertical alignment with said depository element, and means for adjusting the distance apart of said shield members whereby to maintain the

place where they are spaced apart in vertical alignment with said depository element while maintaining the inclination of the shield members.

5 7. In a mobile unitary device of the class described, the combination with a pedestal, of a drum rotatably carried thereon, one end of said drum having a central opening of smaller diameter than the over-all diameter of the drum to provide a conical end for the drum, a frame member mounted in cantilever arrangement on the pedestal and having one end extending through said central opening and another end projecting therefrom, an endless belt conveyor entrained on said frame member, a deflecting shield carried on said frame with the drum and disposed partially over the conveyor longitudinally thereof, said shield comprising a pair of shield members inclined toward each other and spaced apart to provide a restricted opening therebetween in vertical alignment with said conveyor adjacent the longitudinal center line thereof, formations in the drum for lifting particles disposed therein from the bottom of the drum to the top thereof and dropping them toward the conveyor and shield whereby some of the particles fall onto the conveyor and others are deflected back into the drum, mounting means carried on the pedestal below the conveyor frame, a motor mounted on said mounting means, and power transmission mechanism carried by the pedestal engaging the motor, drum, and conveyor respectively for causing the motor to drive both the drum and conveyor, said drum resting by gravity on said pedestal in position to engage said mechanism and being readily separable therefrom.
